UNITED STATES PATENT OFFICE.

HARVEY A. SHIPMAN AND THOMAS M. MORCOM, OF BAKER CITY, OREGON.

DESIGN FOR A RECEPTACLE.

SPECIFIC. —ON forming part of Design No. 31,819, dated November 14, 1899.

Application filed September 7, 1899. Serial No. 729,784. Term of patent 14 years.

To all whom it may concern:

Be it known that we, HARVEY A. SHIPMAN and THOMAS MORCOM, citizens of the United States, residing at Baker City, in the county 5 of Baker and State of Oregon, have invented and produced a new and original Design for a Receptacle, of which the following is a specification.

This invention relates to a new and original design for a receptacle, and the essential features of the same reside in an irregular elliptical body having a convex surface and including a projection at one side of curved form.

15 In the accompanying drawings, Figure 1 is a perspective view of a receptacle embodying the features of the design. Fig. 2 is a horizontal section taken about midway through the receptacle.

20 Similar numerals of reference are employed to indicate corresponding parts in the views. The design in the present instance pertains

to a receptacle, and consists of a body 1, which is hollow and of irregular elliptical form in cross-section. This body has a convex surface 2, continuing into a lower rounded end 3 and merging also into an upper slight concavity 4. At one side of the body is a curved projection 5, which is continuous, with a distinct indentation 6 of curved form on one side 25 and with a less distinct indentation 7 on the opposite side, the latter also being curved.

Having thus described the invention, what is claimed as new is—

The design for a receptacle, herein shown 35 and described.

In testimony that we claim the foregoing as our own we have hereto affixed our signatures in the presence of two witnesses.

HARVEY A. SHIPMAN.
THOMAS MORCOM.
